UNITED STATES PATENT OFFICE

GEORGE E. KRIDER, OF DUNCANSVILLE, PENNSYLVANIA, ASSIGNOR TO McLANAHAN-STONE MACHINE COMPANY, OF HOLLIDAYSBURG, PENNSYLVANIA, A CORPORATION OF PENNSYLVANIA

PADDLE ORE-WASHING MACHINE

Application filed April 19, 1930. Serial No. 445,717.

This invention relates to improved paddle constructions for use and association with washing machinery for ore and stone washing purposes.

More specifically stated, the invention has reference to an improved paddle for use and association with a multiple steel log washer type of machine which, as is well known in the industry, embodies interconnected rotary shafts provided with longitudinally spaced radial paddles such as are employed for the purpose of removing clay from hematite, manganese, ores, limestones, phosphates, rock, gravel, sand and other materials where such impurities are present.

In these types of washing machines, there are two or more inter-geared rotary shafts provided with a multiplicity of radial paddles. Each paddle is of a one piece construction and removably bolted to the shaft. As a general rule the shaft is made up of a plurality of angle irons. In the event of injury or undue wear and tear on the paddle, it is necessary to remove the entire paddle. This is an expensive arrangement.

The purpose of the present invention is to provide a two-part paddle construction including a body portion and a renewable tip or blade portion so that when the blade portion becomes worn it may be replaced in an inexpensive and expeditious manner.

The purpose of the present invention is to provide a renewable paddle tip or blade of an inexpensive and practical form, whereby to improve upon prior patented and marketed devices of this general classification.

In the drawings:

Figure 1 represents a fragmentary portion of an angle iron shaft provided with one of the improved paddle constructions as made in accordance with the present invention.

Figure 2 is a sectional view through the paddle showing a permanent retaining finger or retainer.

Figure 3 is an end or edge elevation of the structure seen in Figure 2.

Figure 4 is a view similar to Figure 2 show-

ing a slightly different form of retaining key.

Figure 5 is an end view of the structure seen in Figure 4.

In Figure 6 is a top plan view thereof. 55

Attention is first invited to Figure 1 wherein the numeral 7 designates generally one of the rotatable paddle carrying shafts. This is here shown as embodying a series of four angle irons 8 assembled in the manner here shown to accommodate the individual paddles generally designated by the numeral 9. These paddles in accordance with the general arrangement in the trade are obliquely arranged. 65

Ordinarily however, each paddle is of one piece form and when it is injured, it is necessary to replace the entire paddle. Hence the desire for a two part paddle wherein the tip may be replaced in a more economical manner. 70

The paddle herein shown comprises a substantially rectangular attaching shank 10 which is fitted between the complemental angle irons and bolts in place by the bolt 11. 75 The protruding head portion 12 is fashioned to provide a keeper and includes a wedge-shaped keyway. The renewable blade is indicated by the numeral 13 and this includes a tapered connecting portion 14 forming the key and fitting slidably in the keyway. This blade occupies the customary angular position with respect to the shaft 7.

In accordance with the present invention, the narrow end of the key 14 is provided with an integral tongue 15 whose free end portion is bent down against the adjacent end of the keeper head 12 as shown in Figures 1 and 2 to prevent displacement of the blade. When however, the blade is especially worn and needs replacement, the bent end of the retaining finger is bent to the dotted line position seen in Figure 2, whereupon the blade is simply slipped out of the keyway and a new blade put in position. 90

In this arrangement, the shank and keeper is removably bolted to the shaft and is itself removable. The blade 13 is individually removable and therefore renewable. Consequently, therefore, this form of blade is of a 100

simplified, compact, convenient and economical type.

In Figures 4 to 6 inclusive, the same general principle of construction is embodied except that the retainer is in the nature of a detachable bar 16 seated in the groove in the bottom of the key 14. The bar is of such length as to permit one end 17 to be bent down to retaining position and the opposite end 18 to be bent up as shown in Figure 4. Thus, by bending the end 17 up the bar and the blade may be removed as a unit. In this arrangement the bar can be re-used, thus making this form of the invention even more economical.

The gist of the invention, it will be understood, is in the combination of a rotary paddle carrying shaft constructed preferably of angle iron and including a two-part blade having a shank portion removably bolted in place and provided with a keeper head of proper angular relationship, together with a readily removable and renewable blade and dependable retaining device therefor.

It is thought that persons skilled in the art to which the invention relates will be able to obtain a clear understanding of the invention after considering the description in connection with the drawings. Therefore, a more lengthy description is regarded as unnecessary.

Minor changes in shape, size, and rearrangement of details coming within the field of invention claimed may be resorted to in actual practice if desired.

I claim:

1. In a structure of the class described, in combination, a rotary shaft embodying a pair of spaced parallel angle irons, a paddle, said paddle including a shank removably bolted between said irons, said shank having a keeper embodying a head provided with a keyway, and a renewable blade having a key removably fitted in said keyway, together with a retaining tongue formed integrally with said key and bendable against said head for maintaining said blade in position.

2. In a structure of the class described, in combination, a rotary shaft embodying a pair of spaced parallel angle irons, a paddle, said paddle including a shank removably bolted between said irons, said shank having a keeper embodying a head provided with a keyway, and a renewable blade having a key removably fitted in said keyway, and a separate bar element co-operable with said key and having one end bent down to retaining position against said head and having the opposite end bent up against the body portion of the blade.

3. As a new product of manufacture, a two-part paddle for use and association with a machine of the class described comprising a removable shank having an angularly disposed head provided with a wedge-shaped keyway and a blade having a wedge-shaped key removably arranged in said keyway, to-

gether with a bendable retaining element carried by said blade and co-operable with said head.

In testimony whereof I affix my signature.

GEORGE E. KRIDER.
